UNITED STATES PATENT OFFICE

120,807

DESIGN FOR A TEXTILE FABRIC

Robert S. Gentile, New York, N. Y.

Application April 22, 1940, Serial No. 91,841

Term of patent 3½ years

To all whom it may concern:

Be it known that I, Robert S. Gentile, a citizen of the United States, residing in New York city, in the county of New York and State of New York, have invented a new, original, and ornamental Design for a Textile Fabric, of which the following is a specification, reference being had to the accompanying drawing, forming a part thereof.

The figure is a plan view of a textile fabric showing my design.

I claim:

The ornamental design for a textile fabric, as shown.

ROBERT S. GENTILE.
